JOSEPH P. CATLIN, OF PLAINFIELD, NEW JERSEY, ASSIGNOR TO WOOD NEWSPAPER MACHINERY CORPORATION, OF NEW YORK, N. Y., A CORPORATION OF VIRGINIA

MEANS FOR PRESERVING FORM ROLLS

Application filed September 10, 1923. Serial No. 661,926.

This invention relates to the inking mechanism of a printing press. The principal objects of the invention are to provide for increasing the life of the composition form rolls now universally used in newspaper printing presses. These rolls, being used constantly to convey the ink from the ink cylinder to the plate cylinder, are considerably heated. When the temperature gets higher than the composition of which they are formed will stand they soften on the surface and have to be taken out and recast. This delays the operation of producing the newspapers and involves expense and trouble.

The principal object of this invention is to provide for avoiding this difficulty without at the same time changing the composition and construction of the form rolls which are now very satisfactory, otherwise.

Reference is to be had to the accompanying drawings, in which

Fig. 1 is a side view partly in section and partly diagrammatic of part of a web perfecting press, showing a preferred embodiment of this invention applied thereto;

Fig. 2 is a plan of the form rolls thereof; and

Fig. 3 is a view similar to Fig. 1 showing a modification.

I have shown the invention as applied to a press having plate cylinders 10 and impression cylinders 11 arranged in the usual way and supplied with ink by a fountain roll 13 and ductor roll 17 to the ink cylinder 14.

Distributing rolls 15 are shown as usual on the ink cylinder and a pair of composition form rolls 16 for delivering ink from the ink cylinder to the plate cylinder.

This invention relates to the form rolls chiefly. For the purpose of preserving them against the melting down above mentioned, I simply provide for cooling their exterior surfaces constantly. This is done in the form shown in Figs. 1 and 2 by the provision of a flattened pipe 9 between the two form rolls and also between the ink cylinder and the plate cylinder. This is supplied with air, gas or vapor under pressure through a pipe 8. This may be of ordinary temperature or may be cooled or refrigerated to give a greater

cooling effect. The pipe 9 is provided with numerous perforations 7, preferably in four rows. Two of them are arranged at the convex sides of the pipe to direct blasts of air against the outside surfaces of the form rolls. The other two are located at the top and bottom to direct air against the plate cylinder and ink cylinder respectively. Thus the surfaces which come in contact with the form rolls will also be cooled, so that, instead of increasing the temperature of the form rolls by their contact therewith they will tend to reduce it.

This constitutes a very simple means for cooling these rolls and keeping them cool so that they will retain their original shape.

In the form shown in Fig. 3 a slight modification is indicated. Here the pipe 8 directs air, vapor, or carbonic acid gas under pressure into the pipe 9 through an open tube 5, so that atmospheric air may be introduced through them, induced by the current passing in. Otherwise the conditions are the same as in Fig. 2.

Instead of forcing air in through the pipes 8 and 6 in any of these forms different kinds of gases can be used including gases which extract heat on expansion. Such gases being delivered under pressure will strike the rolls and cool them more rapidly than ordinary air.

Although I have illustrated and described only two forms of this invention I am aware of the fact that modifications can be made therein by any person skilled in the art without departing from the scope of the invention as expressed in the claims. Therefore, I do not wish to be limited to any of the forms herein shown and described but what I do claim is:—

1. In a printing press, the combination with an ink cylinder, plate cylinder and two form rolls contacting with both and enclosing a space closed except at the ends, of a cooling pipe extending along said space and perforated along four sides to direct jets of cooling fluid against all four of said rolls and cylinders.

2. In a printing press, the combination with an ink cylinder, plate cylinder and two

form rolls contacting with both and enclosing a space, of a cooling pipe extending along said space and perforated to direct jets of cooling fluid against said rolls.

5 3. In a printing press, the combination with the two form rolls, of a nozzle located in the space between said rolls and the plate cylinder for simultaneously cooling the exterior of both of the form rolls and the plate cylinder while the form rolls are in the act of transferring ink to said plate cylinder.

10 In testimony whereof I have hereunto affixed my signature.

JOSEPH P. CATLIN.
